STRIPPING MACHINE

Robert D. Easton, Chicago, Ill., assignor to R. R. Donnelley & Sons Co., Chicago, Ill., a corporation of Illinois

Application August 8, 1932, Serial No. 628,875

16 Claims. (Cl. 11—1)

My invention relates, generally stated, to a machine for applying bonding material, such as glue, or other adhesive, to the opposite faces at opposite edges, respectively, of strip-material, such as fabric used as reinforcement in book-binding and more specifically, though not exclusively, to the assembling of such strips having the adhesive applied thereto as stated, with signatures and end sheets applied to the oppositely disposed glued surfaces, respectively, of the strips.

My invention was devised for use more particularly in the manufacture of books according to the disclosure contained in the application of Harley C. Alger for United States Letters Patent on improvement in Books and the manufacture of same, Serial No. 619,148, filed June 24, 1932, and which involves the securing of the reinforcing strip at one face along one edge to an end signature of the book, and at its other edge, at its opposite face, to an end sheet either single or double page, the portion of the strip which flatwise opposes the end sheet being glued in the binding of the book to the adjacent cover of the book. I do not, however, wish to be understood as intending to limit it to the manufacture of books in accordance with said application.

My primary objects are to provide a machine whereby the adhesive will be applied to the strips as above stated; to assemble the strips with sheets for adherence to the adhesive and particularly signature and end sheets; to provide a simple and positively operating machine for the purposes above stated; and other objects as will be manifest from the following description.

Referring to the accompanying drawings:

Figure 1 is a plan view of a machine constructed in accordance with my invention.

Figure 2 is a longitudinal sectional view of the machine, the section being taken at the line 2—2 on Fig. 1 and viewed in the direction of the arrows.

Figure 3 is a section taken at the lines 3—3 on Figs. 1 and 4 and viewed in the direction of the respective arrows.

Figure 4 is an enlarged fragmentary plan view of the machine.

Figure 5 is an enlarged section taken at the line 5—5 on Fig. 2 and viewed in the direction of the arrows.

Figure 6 is a fragmentary view in vertical sectional elevation the section being taken at the line 6—6 on Fig. 5 and viewed in the direction of the arrows.

Figure 7 is a cross sectional broken view of the product produced by the machine.

Figure 8 is a view in side elevation of the gluing mechanism of the machine showing the means for insuring simultaneous operation of 60 the glue wheels; and

Figure 9, an enlarged fragmentary plan view showing the gluing mechanism.

As a preface to a detailed description of the machine shown it may be stated that it comprises generally means 10 for rotatably supporting a roll 11 of the strip material represented at 12 to be provided with an adhesive, such as glue, and to be assembled with the sheet members such as end sheets one of which is represented 70 at 13 and signatures one of which is represented at 14; means 15 for applying adhesive to opposite faces of the strip material at its opposite lateral edge portions, means 16 and 17 for supporting the sheet members, respectively, side by 75 side with the adjacent edges of the sheet members disposed at different elevations to receive the strip material 12 between them; reciprocating means 18 for feeding the sheet members in the machine; endless conveyor means 19 for 80 receiving the sheet members fed by said reciprocating means and continuing the feed thereof; and means for pressing the sheet members against the adhesive coated portions of the strip material to produce the product of Fig. 7. 85

The particular illustrated machine comprises a frame 20 on which the various means above referred to are supported and having a bed portion 21.

The roll 11 of strip material is supported on 90 the means 10 shown as comprising a reel 22 rotatably mounted at its shaft 23 on the frame of the machine.

The bonding material applying or gluing means 15 to which the strip material 10 extends 95 from the roll thereof comprises two glue receptacles 24 and 25 supported on the machine frame and into which glue wheels 26 and 27 mounted on shafts 28 and 29, respectively, journaled in the walls of the glue pots, extend, doctor blades 100 30 and 31 co-operating with these wheels to remove excess glue in accordance with common practice. The glue wheels 26 and 27, which are disposed out of alignment longitudinally of the machine as shown co-operate with glue-transfer 105 wheels 32 and 33, respectively, secured to shafts 34 and 35 journaled on the frame of the machine to extend above, and in vertical alignment with, the wheels 26 and 27, respectively, with their peripheries sufficiently close to the peripheries 110

of these wheels to effect the transfer of glue thereto from the wheels 26 and 27, the shafts 34 and 35 carrying other wheels 36 and 37, respectively, which are alined, longitudinally of the machine, with the wheels 33 and 32, respectively.

As the strip of glue desired to be applied in the particular construction shown to the upper side of the strip material 12 at its right-hand edge portion, viewing the strip material as in

10 Fig. 3, is relatively narrow as compared with the strip of glue to be applied to the underside of the strip material at its other edge portion, the wheel 32 is relatively narrow compared with the width of the wheel 33.

15 It may here be stated that the strip material which passes between rolls 38 and 39 journaled on the machine frame and across a roller 40 likewise journaled on the frame, extends over the transfer wheel 32, thence around a roll 41 20 on a shaft 42 journaled in arms 43 on the machine frame, whereby the narrow wheel 32 applies the above referred to narrow strip of glue to the face of the strip material which is uppermost in the travel of the latter to the sheet 25 members to be assembled therewith, the strip material passing from the roll 41 to the transfer wheel 33 over which it extends whereby the other above referred to strip of glue is applied to the underside of the strip material.

30 In the arrangement shown the various wheels comprising the gluing mechanism are positively driven by drive mechanism hereinafter described and connected with a sprocket 28^a on the shaft 28; and to insure the simultaneous 35 rotation of these various wheels, they are operatively connected together by an endless sprocket chain 44 trained over sprockets 45, 46, 47 and 48 on the shafts 28, 29, 34 and 35, respectively, and idler sprockets 49 and 50 on shafts 51 and 45 52, respectively, mounted in the machine frame.

45 The chain 44 is trained around the various sprockets referred to in such position relative thereto that the drive of the glue and transfer wheels 26, 27, 32 and 33 will be in the direction of the feed of the strip material therebetween.

50 The means 16 for supporting one of the sheet members (the end sheet 13 in the arrangement shown) and located to the rear of the gluing mechanism, comprises a plate 53 on the bed 21 of the machine and which at this portion of the machine is formed of slats spaced apart crosswise of the machine, the inner edge portion of the plate 53 inclining downwardly along its length to a position in which its inner terminal edge, which is turned upwardly and outwardly as represented at 54, extends in a plane below the path of movement of the strip material 12.

55 The operator, in applying the end sheet 13 to the plate 53, inserts its inner longitudinal edge 13^a under the flange 54 to the position shown in Fig. 3, the sheet 13 extending at its opposite edge along a guide plate extending upwardly from the bed of the machine.

60 The means 17 for supporting the other sheet member (the signature 14 in the arrangement shown) and located alongside the plate 53, comprises a plate 56 extending lengthwise of the machine and supported to overlap one edge of the strip material 12 but at an elevation above the path of movement of the strip material, and on which plate the inner edge of the signature 14 is supported. The inner edge of the plate 56 is provided with an upwardly extending flange 70 57 forming a stop and guide for the signature

14 the outer edge of which rests on the bed of the machine and extends along a guide plate 58 rising from the bed.

15 The sheet members 13 and 14 applied to the positions as shown and above described are fed along the supporting means 16 and 17, respectively, by the reciprocating means 18 above referred to and comprising the following mechanism:

185 Extending along the machine between the longitudinal sides thereof is a guide rod 60 on which a cross bar 61 is mounted at a slide bearing 62 thereon, the ends of the cross bar 61 sliding along guide rods 60^a supported at opposite longitudinal sides of the machine. The cross bar 61 is provided with two pairs of upright fingers the fingers of one pair of which and represented at 63 and co-operating with the end sheets 13, extend upwardly through the slotted bed and through slots 64 in the plate 90 53 and the fingers of the other pair of which and represented at 65 and co-operating with the signatures 14, extend upwardly through the slotted bed and between the plates 56 and 58.

95 The cross bar 61 is reciprocated, to feed the sheets and signatures along the supporting plates therefor and above described, by means of a connecting rod 66 pivoted at 67 to the slide bearing 62, and at its opposite end to a crank pin 68 carried by a disk 69 secured to a shaft 105 70 journaled on the machine frame and provided with a pulley 71 belted at 72 to a drive pulley 73 driven as by a motor 74 through the medium of speed-reducing mechanism represented at 200 and of any desirable construction, 110 the pulley 73 being connected with the relatively slowly driven shaft 73^a of the speed-reducing mechanism 200.

105 As will be understood, the operator applies the end sheet 13 and the signature 14 to the supporting means 16 and 17 while the cross bar 61 is in the retracted position shown in full lines in Fig. 2 and in the rearward movement of this cross bar the end sheet and signature are slid along their supporting means into a position to 115 be engaged by the endless conveyor means 19 which will now be described.

115 The conveyor means 19 comprise an upper pair of spaced apart endless belts 75 and a lower, relatively wide, endless belt 76 extending 125 directly below the belts 75 and spanning the space therebetween, all of these belts extending longitudinally of the machine. The belts 75 extend at opposite sides of the plane of movement of the strip material 12 and the belt 76 130 extends in longitudinal alinement with the latter. The belts 75 are trained about spaced end pulleys 77 and 78 secured to shafts 79 and 80, respectively, journaled in a supplemental frame 81 having end pieces 82 and 83, this frame being 135 supported for vertical adjustment by means of threaded shafts 84 and 85 journaled in heads 86 and 87 carried by arms 88 and 89 secured at their outer ends to the frame of the machine and extending at their free ends over the frame 81, the lower ends of the shafts 84 and 85 having threaded engagement with recesses in the cross members 82 and 83 whereby the frame 81 may be adjusted vertically by rotation of these 140 shafts.

145 The shafts 84 and 85 are provided at their upper ends with bevel gears 90 and 91 which respectively mesh with bevel gears 92 and 93 secured to a shaft 94 journaled in arms 95 and 96 on the heads 86 and 87, to insure simultane-

60 rotation of the shafts 84 and 85 in the same direction and at the same speed when a hand wheel 97 shown as connected with the shaft 84 is rotated.

5 The belt 75 is shown as extending beneath pulleys 98 and 99 journaled on the frame 81 and over intermediate belt tightening pulleys 100 for maintaining the belt in the desired taut condition.

10 The frame 81 is also provided with parallel series of grooved rollers 101 which extend lengthwise of the machine and are located, respectively, within the confines of the endless belts 75 and are adapted to engage with the lower 15 horizontal reaches of these belts and yieldingly force the latter downwardly. The rollers 101 to this end are journaled at stub shafts 102 on the outer ends of rock members pivoted at their 20 other ends to the sides of the frame 81, with springs co-operating therewith and yieldingly forcing the rolls 101 downwardly.

The mechanisms operating the rollers 101 as stated is the same for each roller and therefore the mechanism for one only thereof is illustrated 25 in Fig. 6 wherein the rock member referred to is represented at 103, the pivotal connection thereof with the frame 81 at 104 and the spring at 105. The rock member 103 is located in an opening 81^a in a side of the frame 81, this opening 30 81^a being so shaped, as shown, as to provide a journaling portion 81^b for the pivoting portion 104 referred to and comprising a cylindrical head on one end of the member 103, the remainder of the walls of this opening being so shaped 35 and spaced apart as to permit the rock member 103 to rock therein, the spring, shown as a coil spring, being located in a recess in the frame side and pressing downwardly against the upper surface of the rock member 103.

40 To prevent lateral displacement of the belts 75 from the pulleys supporting them I provide guide-blocks 101^a containing recesses 101^b along their undersides at which they straddle the belts 75, these blocks being slidably mounted, for adjustment crosswise of the frame, on a rod 81^c secured at its ends to the side members of the frame 81, and associated with adjusting screws 101^c rotatable in the frame 81 and threaded in the blocks 101^a for adjusting the blocks into the 50 desired position.

The belt 76 is trained around rollers 107 and 108 carried by shafts 109 and 110 journaled in a stationary frame 111, the belt 76 passing over rollers 112 and 113 on shafts 114 and 115, respectively, carried by the frame 111 and beneath a belt tightener pulley 116.

The frame 111 is provided with a series of rollers 117 which are located within the confines of the belt 76 and are in vertical alignment, respectively, with the several pairs of rollers 101, each of the rollers 117 co-operating with spring means operating to yieldingly force them upwardly against the upper horizontal reach of the belt 76, as described of the rollers 101.

65 Both of the belts 75 and 76 are shown as positively driven to travel at their opposed horizontal reach portions in the same direction and at the same speed, by means of drive mechanism comprising a gear 118 secured to the shaft 78 and meshing with a gear 119 secured to a shaft 120 journaled on the frame of the machine, the shaft 120 being provided with a sprocket 121 connected by a chain 122 with a sprocket 123 on the shaft 80. The gear 119 meshes with a gear 124 secured to a shaft 125 journaled on the

frame of the machine and carrying a sprocket 126 connected by a chain 127 with the sprocket 128 on the shaft 110.

70 From the foregoing description it will be understood that the end sheets and signatures advanced by the feed mechanism 18 enter between the upper and lower belts 75 and 76 between which they are gripped and positively fed along the machine.

75 During this feeding of the end sheets and signatures pressure is applied to press together the strip material 12 and the end sheets 13 and signatures 14 in the relative positions shown in Fig. 7 to insure adherence of the glue on the strip material to the opposing surfaces of the end sheets and signatures, the means shown for this purpose comprising a plurality of presser devices 129 which are located above the belt 76 and are adapted to press against the upper surface of the signature and the portion of the strip material 12 which overlies the end sheet at the joint between the latter and the signature, the belt 76 forming a backing resisting the pressure exerted by the devices 129, which are shown as each comprising a series of spring tongues 130 by which the pressure referred to is exerted.

80 The spring tongues 130 of each presser device are shown as formed by slotting an edge portion of suitable elastic material, such as spring steel, the other edge of which is rolled upon itself to form a tubular portion 131. The presser devices are mounted at their tubular portions 131 on cross bars 132 secured to the opposite sides of the frame 81 and to which the tubular portions 131 are secured against rotation, the parts 85 being so arranged that the fingers 130, in the movement therebetween of the end sheets, signatures and strip material, will be flexed upwardly and placed under tension thus exerting the desired pressure for insuring the adhesion of 90 the strip material 12 to the end sheets and signatures.

95 In the construction shown the mechanism for driving the sprocket 28^a to drive the wheels of the gluing mechanism comprises a sprocket-chain 28^b engaging the sprocket 28 and a sprocket 120 125^a on the shaft 125, these parts being so proportioned that the surface speed of the wheels of the gluing mechanism will be the same as the surface speed of the belts 75 and 76 and thus the strip material 12 will feed with the sheet members 125 130 135 140 145 150 155 160 165 170 175 180 185 190 195 200 205 210 215 220 225 230 235 240 245 250 255 260 265 270 275 280 285 290 295 300 305 310 315 fed pair of these members, viz., with the minimum space therebetween, to avoid waste of the strip material which would be severed between each adjacent pair of sheet members in any suitable way after passing beyond the feed means 19.

While I have illustrated and described a particular construction of machine embodying my invention, I do not wish to be understood as 10 intending to limit it thereto, as the same may be variously modified and altered without departing from the spirit of the invention.

What I claim as new, and desire to secure by Letters Patent, is:

15. 1. In a machine of the character set forth, the combination of means for supporting, side by side, sheet members, to be connected together by strip material, with their adjacent edge portions spaced apart in a direction crosswise of said sheet members and with strip material disposed in said space and lapping at bonding material-coated surfaces thereof opposite faces of said edge portions, means for moving said sheet members along said first-named means, and 20 means for uniting the bonding material on said strip material to the lapping portions of said sheet members.

2. In a machine of the character set forth, the combination of means for supporting, side by side, sheet members, to be connected together by strip material, with their adjacent edge portions spaced part in a direction crosswise of said sheet members and with strip material disposed in said space and lapping, at bonding material-coated surfaces thereof, opposite faces of said edge portions, means for moving said sheet members along said first-named means, means for uniting the bonding material on said strip material to the lapping portions of said sheet members, and means to which said sheet members are delivered by said second-named means for moving said sheet members and said strip material.

3. In a machine of the character set forth, the combination of means for supporting, side by side, sheet members, to be connected together by strip material, with their adjacent edge portions spaced apart in a direction crosswise of said sheet members and with strip material disposed in said space and lapping, at bonding material-coated surfaces thereof, opposite faces of said edge portions, reciprocatory means for moving said sheet members along said first-named means, and means for uniting the bonding material on said strip material to the lapping portions of said sheet members.

4. In a machine of the character set forth, the combination of means for supporting, side by side, sheet members, to be connected together by strip material, with their adjacent edge portions spaced apart in a direction crosswise of said sheet members and with strip material disposed in said space and lapping, at bonding material-coated surfaces thereof, opposite faces of said edge portions, means for moving said sheet members along said first-named means, means for uniting the bonding material on said strip material to the lapping portions of said sheet members, and means to which said sheet members are delivered by said second-named means for feeding said sheet members and said strip material and comprising opposed endless traveling belts between which the sheet members are gripped.

5. In a machine of the character set forth, the

combination of means for supporting, side by side, sheet members, to be connected together by strip material, with their adjacent edge portions spaced apart in a direction crosswise of said sheet members and with strip material disposed in said space and lapping opposite faces of said edge portions, said means comprising supporting member for said sheet members and guide members adjacent the inner edges of said sheet members the one of said guide members for the lower sheet member having a portion adapted to overlie the sheet member beneath it.

6. In a machine of the character set forth, the combination of means engaging sheet members disposed side by side for feeding the same, with bonding material-coated strip material flatwise opposing faces of said sheet members at their adjacent edges, and means for pressing together said sheet members and strip material.

7. In a machine of the character set forth, the combination of means engaging sheet members disposed side by side for feeding the same, with bonding material-coated strip material flatwise opposing faces of said sheet members at their adjacent edges, and spring fingers operating to press together said sheet members and strip material.

8. In a machine of the character set forth, the combination of means for supporting, side by side, sheet members, to be connected together by strip material, with their adjacent edge portions spaced apart in a direction crosswise of said sheet members, bonding material-applying members positioned to apply bonding material to one face of strip material at one of its lateral margins and to the other face thereof at its opposite lateral margins, the strip material being disposed in the space between said sheet members and lapping at its bonding material-coated surfaces opposite faces of said edge portions, means for moving said sheet members along said first-named means, and means for adhering the bonding material on said strip material to the lapping portions of said sheet members.

9. A machine for uniting strip material, with the adjacent edges of sheet members arranged side by side, comprising means for feeding sheet members with adjacent edges thereof spaced apart in a direction crosswise of the sheet members, means for feeding strip material disposed in the space between said sheet members and lapping the adjacent edge portions of said sheet members at opposite faces thereof, the portions of said strip material at which it laps said sheet members being coated with bonding material, and means for pressing the lapping edge portions of said sheet members into uniting contact with said strip material.

10. In a machine of the character set forth, means to position strip material partially coated with bonding material on opposite faces, said bonding material being along opposite edge portions of the strip material, guide means for the positioning of sheet members in substantial parallelism on opposite faces of said strip and partially overlapping the strip opposite the bonding material thereon, and means operable to unite the bonding material on said strip material to the overlapping portions of said sheet members.

11. In a machine of the character set forth, means to position strip material, guide means for the positioning of sheet members in substantial parallelism on opposite faces of the strip material and partially overlapping the ad-

5 jacent opposite edge portions of the strip material, and means operable to unite said strip material to the overlapping portions of said sheet members by material disposed between the strip material and overlapping portions of the sheet members.

12. In a machine of the character set forth the combination of means operable to feed sheet members disposed side by side in parallelism with strip material flatwise opposing faces of said sheet members at their adjacent edges, and means operable in combination with a securing means to effect relative movement of said sheet members and strip material to secure them together.

13. In a machine of the character set forth, means to position strip material guide means for the positioning of sheet members in substantial parallelism on opposite faces of and out 20 of contact with the strip material and partially overlapping the adjacent opposite edge portions of the strip material, and means operable to unite said strip material to the overlapping portions of said sheet members by material disposed 25 between the strip material and overlapping portions of the sheet members.

14. In a machine of the character set forth, means to position strip material, guide means for the positioning of sheet members in substantial parallelism on opposite faces of the strip material and partially overlapping the adjacent opposite edge portions of the strip material, and

means located beyond said guide means in the line of advance of the strip material and sheet members operable to unite said strip material to the overlapping portions of said sheet members by material disposed between the strip material and overlapping portions of the sheet members.

15. The method of uniting sheet members with their edges in substantial registry by means of a strip member bonded to alternate faces of the sheet members at the margins of each, which comprises: applying adhesive material to one of each of the surfaces to be bonded; positioning the sheet members in spaced apart relation in a direction laterally thereof with their edges substantially in registry; positioning the strip member in said space with its margins lapping the margins of said sheet members; and bringing the adhesive carrying surfaces into contact with the opposing surfaces.

16. The method of uniting strip material with adjacent edges of sheet members arranged edge to edge which comprises, applying adhesive material to opposite margins of opposite faces of the strip material, placing the members in a position relatively spaced apart, with their edges substantially in registry, and the strip material in said space to lap both sheet members, and bringing the sheet members into contact with said adhesive coated surfaces of the strip material.
